DESIGN FOR A FRONTPiece FOR EYEGLASSES

Louis L. Adolf, New York, N. Y., assignor to
Comptone Company, New York, N. Y.

Application March 22, 1946, Serial No. 127,803

Term of patent 14 years

(Cl. D57—1)

To all whom it may concern:

Be it known that I, Louis L. Adolf, a citizen of the United States of America, residing in the city, county, and State of New York, have invented a new, original, and ornamental Design for a Front Piece for Eyeglasses, of which the following is a specification, reference being had to the accompanying drawing, forming part thereof, in which

Fig. 1 is a front elevational view of a front piece for eyeglasses, showing my new design;

Fig. 2 is a side view of the same, and

Fig. 3 is a top plan view of the same.

I claim:

The ornamental design for a front piece for eyeglasses, substantially as shown.

LOUIS L. ADOLF.
